ELECTRON DISCHARGE DEVICE

George Ross Kilgore, Verona, N. J., assignor to
 Radio Corporation of America, a corporation of
 Delaware

Application April 24, 1942, Serial No. 440,299

19 Claims. (Cl. 250—27.5)

1

My invention relates to electron discharge devices, more particularly to such devices utilizing beam deflection and suitable for use at ultra high frequencies.

In tubes of the type under consideration a beam of electrons is directed between a pair of deflecting electrodes toward an apertured electrode behind which is usually placed a collector. Alternating voltages are applied to the deflecting electrodes to cause the electron beam to be deflected across the aperture to thus control the amount of current flowing to the collector which may be used as an output electrode. In such types of tubes the deflection sensitivity drops off as the frequency at which the tube is operated is increased. Efforts have been made to increase the deflection sensitivity or the transconductance of the tube, but such efforts have not met with a great deal of success.

Conventional tubes are also subject to the limitation that, when operated at ultra high frequencies, the input circuit tends to be of low resonant impedance resulting in an excessive amount of power being required to drive the tube. This decreases the effective power gain of the tube when operated as an amplifier. Fundamental causes of low resonant impedance include, among other things, radiation and resistance losses due to high circulating current in electrodes and leads. Electron loading also results from the inter-action of the electron stream and the circuits connected to the tube and includes degenerative and regenerative effects caused by common lead impedances.

It is an object of my invention to provide an electron discharge device of the beam deflection type which is particularly suitable for use at high frequencies and which has a comparatively high transconductance.

It is another object of my invention to provide such a device utilizing an input circuit having high resonant impedance, thus making more effective use of the driving power.

A further object of my invention is to provide such a device in which undesired coupling, due to common leads and ineffective shielding, is reduced to a minimum.

The novel features which I believe to be characteristic of my invention are set forth with particularity in the appended claims, but the invention itself will best be understood by reference to the following description taken in connection with the accompanying drawing in which Figure 1 is a longitudinal schematic section of one form of an electron discharge device made according to

2

my invention and its associated circuit, Figure 2 is a section taken along the line 2—2 of Figure 1 and Figure 3 is a longitudinal schematic section of the device shown in Figure 1.

Referring to Figure 1, an electron discharge device made according to my invention comprises an evacuated envelope 10 containing at one end a cathode 11 and at the other end a collector 12 for receiving electrons generated by cathode 11. Next adjacent to the cathode is a beam forming and shielding cup-shaped member 13 provided with an aperture 13' through which the beam of electrons is directed between a pair of rod electrodes 14 and 15 for determining the direction of the beam through the various electrodes, the proper biasing voltages being supplied by means of voltage source 16 in the form of a voltage source and potentiometer arrangement. Positioned between the collector and the beam forming member 13 is a resonant cavity tank circuit or cavity resonator comprising a tubular member 17 closed at one end by means of the member 18 and provided with aperture 18' registering with the beam directed from the cathode 11. A cone-shaped partition 19 provided with aperture 19' is positioned intermediate the ends of the member 17 to provide between the closing member 18 and partition 19 a resonant cavity. The other end of the tubular member 17 is closed by means of the member 20 provided with tubular inwardly extending member 21 in which the collector 12 is positioned and by which it is shielded and screened from the field within the resonant cavity. The chamber formed between the partition 19 and closure member 20 provides an output resonant cavity which is set and maintained in oscillation, in a manner now well understood, when groups of electrons pass across the gap 21'. It is obvious that this second resonant cavity or output resonant cavity tank circuit could be eliminated and the collector utilized as an output electrode, the output circuit being connected to this electrode.

In accordance with my invention I provide between the apertured disc member 18 and partition 19 a pair of deflecting electrodes 22 and 23 supported by means of the strip supporting members 22' and 23', these electrodes deflecting the beam of electrons across aperture 19' during operation of the electron discharge device.

The surface of member 17 is provided with an aperture 17' into which the reentrant portion 10' of envelope 10 extends and into which an input coupling loop 24 extends to excite the resonator during operation of the device. Another aper-

ture 17" is provided in the output resonant cavity tank circuit into which a second reentrant portion 18" of the envelope 10 extends to permit a coupling loop 25 to be extended within the cavity to be coupled with the radio frequency field generated within the cavity. A source of voltage 26 is provided from which the various biasing voltages may be obtained.

In operation a beam of electrons is formed by means of cathode 11 and beam forming and shielding electrode 13, the direction of the beam being easily controlled by means of the directing electrodes 14 and 15. The beam is directed through aperture 18', between deflecting electrodes 22 and 23 which in one mode of operation of the resonant cavity tank circuit between the end member 18 and partition 19, produces a deflecting voltage across the electrodes 22 and 23. As a result the electron beam is deflected across the aperture 18' inducing a radio frequency voltage in the output cavity between partitions 19 and closure member 20 when the groups of electrons pass across gap 21' and are collected by collector 12, which is thoroughly shielded by means of the reentrant tubular member 21. The deflecting electrodes 22 and 23 have, preferably, a length equal to approximately the distance travelled by an electron during a half period of the natural frequency of oscillation of the input resonant cavity tank circuit formed between closure member 18 and the partition 19. I have found this produces a maximum deflection sensitivity for this kind of operation.

Figure 3 shows a schematic longitudinal section of a modification of my invention. In this embodiment a cathode 30 is provided with a heater 31 positioned at one end of the device and collector 32 is positioned at the other end of the device, this collector also serving as an output electrode. Next adjacent the cathode is a cylindrical beam forming and directing member 33, preferably in the form of a tubular member closed at both ends by means of apertured disc members 33' and 33''. Within the tubular member 33 but insulated therefrom are beam directing electrodes 34 and 35, which derive their potential from the voltage source 36. Positioned between the beam forming member 33 and collector 32 is a resonant cavity tank circuit or cavity resonator 37 in the form of an annular hollow member of conducting material. Mounted on opposite walls are deflecting electrodes 38 and 39 between which the beam is directed to be deflected across the closure member 40' provided with an aperture bisected by member 46, thus giving a double aperture and providing certain desirable characteristics. Tubular extensions 40 and 41 extending outwardly from the cavity are provided with cup-shaped elements 42 and 43, which are sealed to the insulating cup-shaped members 44 and 45 for supporting the input and collector electrodes and providing with the resonant cavity an evacuated envelope. An aperture 47 is provided in the resonant cavity 37. The aperture is surrounded by collar 48 to which is sealed a reentrant insulating cup-shaped member 49 into which the input coupling loop 50 extends for exciting the resonant cavity. The output voltage is impressed on the output transformer 51 and the various biasing voltages are taken from the source 52.

In operation the beam of electrons from cathode 30 is properly directed through various apertures by means of electrodes 34 and 35 and the electrons are accelerated through the apertured

closure member 40' and between the deflecting electrodes 38 and 39 between which appears a deflecting radio frequency voltage, it being understood in the usual mode of operation that the radio frequency currents circulate from electrode 38 around the inside of the tank to the other electrode 39, the magnetic field lying perpendicular to the radio frequency voltage and currents in a manner now well known.

10. Thus in both arrangements a high transconductance results since the length of the deflecting electrodes bears a definite relationship to the operating input frequency. Because of the enclosed circuit utilized the losses are reduced substantially, thus making more power available for driving the input circuit and the tube. Because of the enclosed circuits and because of the large shielding mass between the input and output circuits, undesired coupling is reduced to a minimum so that the device lends itself particularly to use as an amplifier, although it is suitable for use as an oscillator with small changes providing feedback.

15. While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

20. 35. What I claim as new is:

1. An electron discharge device having a cathode for supplying a beam of electrons, a collector for said electrons, a cavity resonator for containing an electromagnetic field having a resonant frequency and positioned between said cathode and said collector, said cavity resonator having an opening in the wall thereof through which said beam of electrons is to be directed, oppositely disposed deflecting electrodes positioned within said cavity resonator to lie within said electromagnetic field and between which said beam of electrons passes during operation of said electron discharge device, each of said deflecting electrodes being separate from and supported by and electrically connected to a different portion of the inside wall of said resonator, said resonator having a second opening in another part of its wall aligned with said first opening and across which said beam of electrons is deflected by said deflecting electrodes during operation of said electron discharge device.

2. An electron discharge device having cathode means for supplying a beam of electrons, a cavity resonator for containing an electromagnetic field and positioned adjacent said cathode means and having oppositely disposed apertures in opposite walls thereof through which the beam of electrons is to be directed, and a pair of deflecting elements separate from the wall of said cavity resonator within the cavity resonator positioned next adjacent said apertures and connected to the inside walls of said cavity resonator to lie within said electromagnetic field and between which said beam of electrons is to be directed to be deflected thereby, and an output electrode system including a member having a pair of apertures through which the beam of electrons is alternately directed during operation of said electron discharge device.

70. 75. 3. An electron discharge device including a

cathode means for providing a beam of electrons and receiving means for said electrons, and other means positioned between said cathode means and said receiving means for deflecting said electron beam and including a closed hollow conducting member for containing an electromagnetic field having apertures in different portions of the wall thereof through which the electron beam is to be directed, and oppositely disposed deflecting electrodes separate from the wall of said closed hollow conducting member within said enclosed hollow conducting member between which said beam passes, each of said deflecting electrodes being supported from and electrically coupled to a different part of the inside wall of said enclosed conducting member to lie within said electromagnetic field, and means positioned between said receiving means and said deflecting electrodes and having a pair of adjacent apertures across which said beam is to be deflected.

4. An electron discharge device including cathode means for providing a beam of electrons, and receiving means for receiving said electrons, and other means positioned between said cathode means and said receiving means for deflecting said electron beam, and including a hollow conducting member for containing an electromagnetic field and having registering apertures in opposite walls thereof through which said beam of electrons is to be directed, and a deflecting electrode positioned within said hollow conducting member and electrically connected to the inside wall of said hollow conducting member next adjacent one aperture, and another deflecting electrode positioned within said hollow conducting member and electrically connected to the inside wall of the conducting member next adjacent the registering aperture, said deflecting electrodes being separate from the walls of said hollow conducting member and oppositely disposed within said hollow conducting member to lie within said electromagnetic field the path of said beam lying between said deflecting electrodes, and a member positioned between the deflecting electrodes and the receiving means and having an aperture across which said beam is to be deflected.

5. An electron discharge device including cathode means for providing a beam of electrons, and receiving means for said beam of electrons, a cavity resonator for containing an electromagnetic field and positioned between said cathode means and receiving means and having registering apertures in opposite walls thereof through which said beam is to be directed, and deflecting electrodes independent of the wall of the cavity resonator positioned within said cavity resonator, said deflecting electrodes being oppositely disposed, one of the deflecting electrodes being electrically connected to the inside wall of the cavity resonator next adjacent one aperture, and another deflecting electrode being connected to the inside wall of the cavity resonator next adjacent the other aperture, said deflecting electrodes being within said resonator to lie within said electromagnetic field, and means provided with an aperture across which said beam is to be deflected and positioned between the receiving means and the deflecting electrodes.

6. An electron discharge device including cathode means for providing a beam of electrons, and receiving means for said beam of electrons, a cavity resonator for containing an electromagnetic field and positioned between said cathode

means and receiving means and having registering apertures in opposite walls thereof through which said beam is to be directed, and deflecting electrodes separate from the walls of said cavity resonator positioned within said cavity resonator to lie within said electromagnetic field, said deflecting electrodes being oppositely disposed, one of the deflecting electrodes being electrically connected to the inside wall of the cavity resonator next adjacent one aperture, and another deflecting electrode being connected to the inside wall of the cavity resonator next adjacent the other aperture, and means positioned between the receiving means and said deflecting electrodes and having a pair of adjacent apertures across which said beam is to be deflected.

7. An electron discharge device having cathode means for supplying a beam of electrons and a collector for receiving said electrons, and means positioned between the cathode means and collector and including a cavity resonator for containing an electromagnetic field having registering apertures disposed in opposite walls thereof through which said beam is to be directed, and a pair of deflecting electrodes separate from the wall of said cavity resonator and positioned intermediate said apertures within said resonator to lie within said electromagnetic field and on opposite sides of the beam path directed therethrough, and supporting and conducting means connected between said deflecting electrodes and the inside wall of the hollow conducting member intermediate the apertures.

8. An electron discharge device having cathode means for supplying a beam of electrons and a collector for receiving said electrons, and means positioned between the cathode means and collector and including a first cavity resonator for containing an electromagnetic field and having registering apertures disposed in opposite walls thereof through which said beam is to be directed, and a pair of deflecting electrodes separate from the walls of said cavity resonator positioned intermediate said apertures within said resonator to lie within said field and on opposite sides of the path of the beam directed therethrough, and supporting and conducting means connected between said deflecting electrodes and to the inside wall of the first cavity resonator intermediate the apertures, and a second cavity resonator positioned between said first cavity resonator and said collecting means and through which said beam is to be directed.

9. An electron discharge device having cathode means for providing a beam of electrons, a collector for receiving said beam of electrons, and a pair of adjacent cavity resonators each for confining an electromagnetic field and positioned between the cathode means and collector and having a plurality of aligned apertures through which the electron beam is directed, deflecting electrodes separate from and positioned within the first cavity resonator to lie within the electromagnetic field and through which the beam path passes and between which the beam is to be directed for deflecting the electron beam across an aperture between the cavity resonators, said deflecting electrodes being supported by means of conducting strips connected to the inside wall of the first of said cavity resonators intermediate the apertures of the first cavity resonator.

10. An electron discharge device having cathode means for providing a beam of electrons, a collector for receiving said beam of electrons, and a pair of adjacent cavity resonators positioned

between the cathode means and collector and having a plurality of aligned apertures through which the electron beam is to be directed, deflecting electrodes positioned within the first cavity resonator through which the beam path passes and between which the beam is to be directed for deflecting the electron beam across an aperture between the cavity resonators, said deflecting electrodes being supported by means of conducting strips connected to the inner wall of the first of said cavity resonators intermediate the apertures of the first cavity resonator, said second cavity resonator being provided with a reentrant portion having an opening registering with the apertures, said collector being positioned within said reentrant portion.

11. An electron discharge device having a cathode for supplying electrons, a collector for said electrons, a tubular member positioned between said cathode and said collector and having a closure member at each end thereof, and a partition intermediate said closure members, said closure members and said partition being provided with aligned apertures, a pair of deflecting electrodes positioned between a closure member adjacent said cathode and said partition and comprising a pair of oppositely disposed elements parallel to the beam path and strap-like elements supporting and electrically connecting said deflecting electrodes from the inner wall of the tubular member intermediate said last closure member and said partition, a reentrant tubular member extending from the closure member adjacent said collector and providing with said partition a gap across which the beam path of electrons passes.

12. An electron discharge device having a cathode for supplying electrons, and means adjacent said cathode for forming said electrons into a beam, a collector for said electrons, a tubular member positioned between the beam forming means and said collector and having a closure member at each end thereof, and a partition intermediate said closure members thereby forming two successive cavity resonators, said closure members and said partition being provided with aligned apertures, a pair of deflecting electrodes positioned between the closure member adjacent the beam forming means and said partition and comprising a pair of oppositely disposed elements parallel to the beam path and strap-like elements supporting and electrically connecting said deflecting electrodes with the inner wall of the tubular member intermediate said last closure member and said partition, a reentrant tubular member extending from the closure member adjacent said collector and providing with said partition a gap across which the beam path of electrons passes, the first cavity resonator having an aperture into which an input coupling loop may be extended, and the second cavity resonator having another aperture into which an output coupling loop may be extended.

13. An electron discharge device having a cathode for supplying electrons, and means adjacent said cathode for forming said electrons into a beam, a collector for said electrons, a tubular member positioned between the beam forming means and said collector and having a closure member at each end thereof, and a partition intermediate said closure members thereby forming two successive cavity resonators, said closure members and said partition being provided with aligned apertures, a pair of deflecting electrodes positioned between the closure member adjacent the beam forming means and said partition and

comprising a pair of oppositely disposed elements parallel to the beam path and strap-like elements supporting and electrically connecting said deflecting electrodes with the inner wall of the tubular member intermediate said last closure member and said partition, a reentrant tubular member extending from the closure member adjacent said collector and providing with said partition a gap across which the beam path of electrons passes, said collector being positioned within said reentrant tubular member, and beam directing electrodes positioned within the beam forming means for directing the beam through the apertures in the partition and closure members during operation of said electron discharge device.

14. An electron discharge device having a cathode for supplying electrons and a collector for said electrons, means including a cavity resonator positioned between the cathode and collector and having apertures in opposite walls thereof, a deflecting electrode extending inwardly of said cavity resonator and positioned adjacent one aperture and an oppositely disposed deflecting electrode positioned adjacent the other aperture, outwardly extending tubular extensions around said apertures and each provided with an apertured closure member through which the beam of electrons is to be directed.

15. An electron discharge device having a cathode for supplying electrons and a collector for said electrons, means including a cavity resonator positioned between the cathode and collector and having apertures in opposite walls thereof, a deflecting electrode extending inwardly of said cavity resonator and positioned adjacent one aperture and an oppositely disposed deflecting electrode positioned adjacent the other aperture, outwardly extending tubular extensions around said apertures and each provided with an apertured closure member through which the beam of electrons is to be directed, and a beam forming and directing means positioned between the cathode and one of the apertured closure members, and including a hollow conducting member and a pair of beam directing electrodes.

16. An electron discharge device having a cathode for supplying electrons and a collector for said electrons, means including a cavity resonator positioned between the cathode and collector and having apertures in opposite walls thereof, a deflecting electrode extending inwardly of said cavity resonator and positioned adjacent one aperture and an oppositely disposed deflecting electrode positioned adjacent the other aperture, outwardly extending tubular extensions around said apertures and each provided with an apertured closure member through which the beam of electrons is to be directed, and cup-shaped members sealed to said tubular extensions on said cavity resonator and forming with said cavity resonator an envelope for the cathode and collector electrode.

17. An electron discharge device having a cathode for supplying electrons and a collector for said electrons, means including a cavity resonator positioned between the cathode and collector and having apertures in opposite walls thereof, a deflecting electrode extending inwardly of said cavity resonator and positioned adjacent one aperture and an oppositely disposed deflecting electrode positioned adjacent the other aperture, outwardly extending tubular extensions around said apertures, each extension having an apertured closure member through which the beam of electrons is to be directed, and cup-shaped members

sealed to said tubular extensions on said cavity resonator and forming with said cavity resonator an envelope for the cathode and collector electrode, and a third aperture in said cavity resonator and a reentrant cup-shaped member sealing said aperture, said last cup-shaped member being adapted to receive a coupling loop within said aperture.

18. An electron discharge device having a cathode for supplying a stream of electrons and a collector for said electrons, a cavity resonator positioned between the cathode and collector and having apertures in opposite walls thereof, a deflecting electrode extending inwardly of said cavity resonator from the wall thereof and adjacent one of said apertures, and a second deflecting electrode positioned opposite the first and supported by and from the wall of the cavity resonator adjacent the other aperture, outwardly extending tubular extensions surrounding said apertures each having an apertured closure member at the free end thereof, cup-shaped flange extensions secured to said tubular members and closure members sealed to said flange members and providing with said cavity resonator an envelope, and beam forming and directing means

10

positioned between said cathode and one of the tubular extensions of said cavity resonator.

19. An electron discharge device having a cathode for supplying a stream of electrons and a collector for said electrons, a cavity resonator positioned between the cathode and collector and having apertures in opposite walls thereof, a deflecting electrode extending inwardly of said cavity resonator from the wall thereof and adjacent one of said apertures, and a second deflecting electrode positioned opposite the first and supported by and from the wall of the cavity resonator adjacent the other aperture, outwardly extending tubular extensions surrounding said apertures and having apertured closure members at the ends thereof, cup-shaped flange members secured to said tubular extensions and closure members sealed to said flange members and providing with said cavity resonator an envelope, and beam forming and directing means positioned between said cathode and one of the tubular extensions of said cavity resonator, the closure member adjacent said collector having a double aperture.

GEORGE ROSS KILGORE.
